E. T. BUSSELL.

Self Adjusting Uterine Cautery.

No. 16,680.

Patented Feb. 24, 1857.

Inventor:

Erastus T. Bussell

UNITED STATES PATENT OFFICE.

ERASTUS T. RUSSELL, OF SHELBYVILLE, INDIANA.

CAUTERIZING-SYRINGE.

Specification of Letters Patent No. 16,680, dated February 24, 1857.

To all whom it may concern:

Be it known that I, ERASTUS T. RUSSELL, of Shelbyville, in the county of Shelby and State of Indiana, have invented a new and Improved Instrument for Making Application of Medicinal Agents Directly to the Vagina and Uterus of Females; and I do hereby declare that the following is a full and exact description, to wit:

10 The nature of my invention consists in providing afflicted females with an instrument, so self adjusting in its operation when introduced into the vagina, as to enable them to effectually apply remedies in im-
15 palpable powder, or otherwise, for the removal of prolapsus uteri, vaginitis, dysmenorrhea, ulcerated os tincae, gonorrhea, &c.

To enable others skilled in the art to 20 make and use my invention, I will proceed to describe its construction and operation.

In what follows, I wish to make the accompanying drawings and figures a part of this specification, like letters and figures re-
25 ferring to like parts.

Figure 1 is the self adjusting uterine cautery, all complete, with plunger and cautering rod pushed entirely up. Fig. 2 represents the instrument with the sponges, 30 cautery, and all drawn into the glass tube, as it must be when inserted in the vagina—the dotted lines showing the expanded spring fingers as they embrace the neck of the uterus, when they are liberated by the 35 partial withdrawal of the glass tube. Fig. 3 is the hollow plunger to which the spring fingers are permanently attached. Fig. 4 is the rod that passes entirely through the hollow plunger, upon the extremity of which 40 is attached a sponge for the purposes before mentioned.

A, is a hollow tube, made of glass or any other non-corrosive substance, four inches long (or more if desired) and about six or 45 seven eighths of an inch in diameter. It is left open at one end and mounted with a metallic cap, 1, at the other. The cap, 1, has an aperture in its center sufficiently large for the free passage of the hollow 50 plunger, B. The hollow plunger, B, is made a little more than four inches long, and upon one end is attached a milled round thumb button, 2, and at the other from three to six expanding spring fingers are 55 soldered, leaving an aperture in the center for the free passage of the cautery rod, C.

The spring fingers, a, a, a, a, a, a, diverge at equal distances from each other, so that their ends, (for the attachment of sponge,) occupy a diameter of about one and a half 60 inches, or more. The cautery rod, C, is made a little longer than the hollow plunger, B, and spring fingers included. Upon one end is fastened a milled button, 3, and the other end is flattened and perforated for 65 stitching on a cautering sponge. These perforations are represented at d, d. I remark here, that any other absorbent, of fibrous substance, may be used instead of sponge for mounting the uterine ends of the 70 expanding spring fingers, a, a, a, a, a, a, as well as for the center cautery, (as represented at b, b, b, b, b, c,) but, as a general practice sponge, fine and soft, is sufficient.

75

In the construction of this instrument, I prefer glass to any other material for the large or outer tube, A, but, for the hollow plunger, cap, and thumb buttons as also center rod, almost any metal will do providing 80 the exposed parts are electroplated, or otherwise covered with some of the precious or non-corroding metals. I prefer that this coating be of silver.

The spring fingers must be made of metal 85 sufficiently elastic to insure their free expansion when desired, to embrace the neck of the uterus, in making medicinal applications. They must also be protected from corrosion, as well as other portions of the in- 90 strument. The necessity for this precaution, grows out of the fact that, in the treatment of ulcerated os tincae it is indispensably necessary to use nitrate of silver or other caustic substances that will rapidly corrode the 95 baser metals:—In the treatment of luxated uterus as also vaginitis, sulfate of zinc is a favorite remedy to give tone to the relaxed vagina and constringe the parts:—and therefore another reason why the instrument must 100 be as indestructible to such agencies as possible and practicable.

The mode of application of remedies by this instrument is simple—may be readily comprehended by any female—so that she 105 can just as safely and certainly apply the prescriptions of her physician as he could do with the aid of a speculum. When it is desired to cauterize, or apply any milder treatment to the mouth of the uterus, the 110 patient is furnished with the necessary medicine, in powder, which she is directed to

place upon the center sponge, *c*, which she must draw back of the others a short distance,—in this condition they are all drawn into the glass tube. The glass tube is then 5 introduced into the vagina until the end of it comes in contact with the mouth of the uterus. At that point the hollow plunger is pressed against the ostincae (with its sponge &c,) while the glass tube is withdrawn just 10 enough to liberate the spring fingers, when they open out and grasp the neck of the uterus—passing their sponge extremities up around the same into the vaginal cul-de-sac. Here they hold the uterus steady, and guide 15 the center sponge (which is operated by the rod *C*,) up into the mouth of the uterus,—which is inevitable from the very nature of the instrument. The sponge on the spring fingers serves as a protection as well as a 20 means of cleansing to this vaginal cul-de-sac—which cannot be reached in all its parts by any other instrument, especially where there is a bad retroversion of the uterus.

The instrument is used for the application 25 of other remedies in a similar way.

If a physician desires to get up a galvanic, vitalizing influence in the neck of the uterus and contiguous parts, he can do so by means

of this instrument alone. He can use two remedies at the same time—of opposite 30 galvanic qualities—each having a metallic base—put one on the cauterizing or center sponge, the other on the outside of the tufts of sponge on the spring fingers—in this relation to each other they are introduced 35 and separately applied, though unmixed, yet applied with the same instrument at the same instant, one to the cervix uteri and vaginal cul-de-sac, while the other is applied within the lips of the mouth of the uterus—thus 40 getting up a most genial and happy galvanic current in the vicinity, curative in a preëminent degree.

What I claim as my invention, and desire 45 to secure by Letters Patent, is,

The combination of hollow plunger, *B*, with cauterizing rod, *C*, incased, and divergent spring fingers with absorbent bulbous extremities, all connected with cylindrical tube *A*, substantially as herein set forth, and 50 for the purposes specified.

ERASTUS T. RUSSELL.
